STANDARD FOR USE IN SUPPORTING
HORIZONTAL BOOKSHELVES

Phillip E. Miller, 1861 Heatherdale Ave.,
San Jose, Calif. 95126

Filed July 16, 1969, Ser. No. 18,225

Term of patent 14 years

Int. Cl. D6—99

U.S. Cl. D33—3

FIG. 1

FIG. 3

FIG. 2

FIG. 1 is a perspective view of a standard for use in supporting horizontal bookshelves showing my design;

FIG. 2 is an elevational view showing the side opposite that shown in FIG. 1; and

FIG. 3 is a top plan view.

The end of the article not shown in FIG. 1 is like the end shown.

I claim:

The ornamental design for a standard for use in supporting horizontal bookshelves, substantially as shown.
